UNITED STATES PATENT OFFICE.

DAVID LAKE AND EDWIN W. CRELLIN, OF PHILADELPHIA, PENNSYLVANIA,
ASSIGNORS OF ONE-HALF TO ALVAN MARKLE AND JOHN W. CRELLIN,
OF HAZLETON, PENNSYLVANIA.

SCREW-CUTTING MACHINE.

SPECIFICATION forming part of Letters Patent No. 705,538, dated July 22, 1902.

Application filed August 5, 1901. Serial No. 70,978. (No model.)

To all whom it may concern:

Be it known that we, DAVID LAKE and EDWIN W. CRELLIN, citizens of the United States, and residents of Philadelphia, Pennsylvania, have invented certain Improvements in Screw-Cutting Machines, of which the following is a specification.

Our invention relates to certain improvements in screw-cutting machines in which the bar to be threaded is fed to a rotary cutter by means of mechanism operated through the medium of a lead-screw.

The object of our invention is to simplify the construction of such a machine, to provide means whereby a screw having two or more threads can be accurately cut, and to so construct the head of the machine that a keyway can be readily cut in a rod, as fully described hereinafter.

20 In the accompanying drawings, Figure 1 is a side view of our improved screw-cutting machine. Fig. 2 is a plan view. Fig. 3 is a longitudinal sectional view on the line 3 3, Fig. 2. Fig. 4 is an end view. Fig. 5 is an enlarged transverse sectional view on the line 5 5, Fig. 1. Fig. 6 is a transverse sectional view on the line 6 6, Fig. 1. Fig. 7 is a sectional plan view on the line 7 7, Fig. 5.

A is the bed-plate of the machine, supported on suitable legs A' A'. On the edge of the bed-plate is a flange a, which forms a drip-catcher for oil or other lubricant, which is freely used in operating screw-cutting machines. Secured to the bed-plate is an undercut slideway B, upon which the carriage D travels and on which the guide E can be adjusted. This slideway extends the full length of the machine in the present instance.

F is a lead-screw running parallel with the slideway B and mounted in a bearing carried by the end frame G and in a bearing G', secured to the opposite end of the bed-plate of the machine.

H is the driving-shaft, mounted in a long bearing G², projecting from the frame G. On one end of this shaft H is a belt-pulley h, and on the opposite end is a pinion h'. The shaft H is hollow, made so to receive the spindle I, by which the cutter is driven. This spindle is splined, and a key on the shaft H en-

ters the spline, so that the spindle will turn with the shaft, but will freely slide longitudinally therein when it is found necessary to adjust the cutter. The shaft H is geared to the lead-screw F through the following train 55 of gears, Fig. 4: The pinion h' meshes with a gear-wheel h² on a stud H', and on this stud is a pinion h³, which meshes in turn with a gear-wheel h⁴ on a stud H², and on this stud is a pinion h⁵, which meshes with a gear-wheel 60 f², carried by a stud F', adjustable on an arm G³. The arm has a curved slot, as shown, and the stud F' can be adjusted in the slot to or from the screw-shaft F, according to the diameter of the gear-wheel f on the shaft F 65 and the gear-wheel f' on the stud F', with which the gear-wheel f meshes. By changing the gear-wheel f and adjusting the stud F' the screw-shaft can be revolved at a greater or less speed.

The carriage D, as mentioned above, travels on the slideway B, being driven forward or backward by the lead-screw F. On the carriage is a bearing d for the chuck-spindle J, and on the end of this spindle is a gear-wheel j, held to the spindle by a nut j'. The gear-wheel j meshes with an intermediate wheel k, carried by two pivoted arms K K', the arm K being pivoted at k', at the side of the bearing d, and the other arm K' is pivoted 80 at k² above the bearing, as illustrated in Fig. 5. These two arms K K' are slotted and can be secured in their adjusted positions by means of a bolt k³ and nut k⁴. The gear-wheel k is mounted on the bolt k³, being held to the 85 bolt by a nut k⁵. The intermediate wheel k meshes with a pinion l on a sleeve L, loose on the screw F. This pinion l is keyed to the sleeve and is held in place by a nut l'. By the above-described construction the sleeve L can 90 be driven at any speed desired by simply changing the intermediate wheel k and the wheel j, the slotted arms forming an adjustable bearing for the spindle of the wheel k. In order to prevent the sleeve moving longitudinally independent of the carriage D, we mount on the carriage a forked arm L², which rests in an annular groove in the sleeve L, as shown in Figs. 5 and 7.

On the sleeve L is a pinion l⁵, which may 100

be used in connection with a second gear-wheel on the stud k^3 when it is desired to change the speed of the sleeve L to a greater extent than by the train of gears described 5 above.

L' is a second sleeve, having a key l^3 , which enters a spline f in the lead-screw F. This spline preferably extends from one end of the screw to the other.

10 The two sleeves L and L' are flanged, as shown, and passing through the flanges is a tapered pin l^4 , which confines the sleeve L' to the sleeve L, so that when the shaft F is turned both sleeves must turn with the shaft, 15 and thus motion is imparted to the chuck-spindle J through the train of gears above described.

M is a clutch mounted on the carriage D and has two jaws $m m$, which can be moved 20 toward and from the screw F by a cam-disk m' , carried by the shaft m^2 , having an operating-wheel. This form of clutch is common in machine-tool practice, where it is desired to throw a carriage or slide into and out of 25 control of the lead-screw.

On the end of the spindle J is an ordinary form of split chuck j^2 , having a tapered periphery, which is threaded, and on the chuck is a nut j^3 . When this nut is turned, the jaws 30 can be drawn tightly on the rod upon which the thread is to be cut.

By constructing the parts in the manner described, so that the sleeve L can be turned independently of the lead-screw, the carriage 35 can be moved forward or backward to a limited extent, so that two or more threads can be cut on a rod by simply shifting the carriage. If it is desired to cut a double thread on a rod, for instance, the cutter is set at the 40 desired angle, and the feed mechanism of the carriage is arranged so that when the machine is set in motion a single thread will be cut with a space wide enough so that when the rod is turned one half-turn the cutter will be 45 in line with the space. This is accomplished by simply withdrawing the pin l^4 and turning the sleeve L one full turn, then inserting the pin l^4 , so as to lock the two sleeves together. By turning the sleeve L the chuck-spindle J 50 is turned, and with it the rod upon which the thread is to be cut. The cutting operation is repeated and the second thread cut upon the rod.

The flanges of the sleeves L L' may have 55 indexed perforations at intervals, so that the machine can be set to cut any number of flanges on a single rod or bar.

We will now describe the carrier for the cutter-head, which is situated at one end of 60 the machine.

Depending from the bed of the machine is a large stud C. This stud in the present instance passes through an opening in the bed-plate A and is screwed into the slideway B. 65 Thus the stud is firmly held to the bed of the machine.

P is a carrier mounted on the stud C. The

lower portion of the carrier P is in the form of a split bearing, the bearing being clamped tightly to the stud by means of a set-screw p , 70 Fig. 1, so that when the carrier is adjusted in position it may be fixed rigidly to the bed of the machine. Secured to the stud C is a disk c. This disk in the present instance is held in place by a bolt c' and prevented from 75 turning by a pin c''. We preferably provide the carrier P with an index-finger p' and graduate the periphery of the disk c. Thus the operator can readily adjust the carrier to the proper angle to cut a screw of the pitch 80 desired. The upper end of the carrier is in the form of a slideway P', and mounted on this slideway is a head R. The position of this head is regulated by a screw r, provided with a hand-wheel r', so that on turning the 85 hand-wheel the head may be raised or lowered. We graduate the hub of the hand-wheel r' and place an index-finger on the bearing p^2 for the screw-shaft r, so that when the said screw-shaft is turned the amount of 90 movement given to the head R is clearly indicated.

Carried by the head R are two bearings R' in the present instance, and mounted in these bearings is a cutter-shaft S. This cutter-shaft carries at one end a cutter s, which is mounted so as to be directly in line with the center of rotation of the carrier on its axis C. No matter in what position the carrier is adjusted the cutter will always be on 95 this center line. The shaft S is threaded at its outer end, and on this threaded portion is a coupling-nut I', which is connected to a rod I² by a universal joint i, and the rod I² is coupled to the rod I by a universal joint i'. 105 The rod I, as before remarked, is keyed to the driving-shaft H, but in such a manner that it can slide longitudinally in the shaft when it is necessary to adjust the head R or the carrier P. On the cutter-shaft in the 110 present instance is a bevel-wheel s', which meshes with a bevel-wheel s² on a short shaft s³, projecting at right angles to the shaft S. The outer end of this shaft s³ is threaded, so 115 that the coupling I' can be readily secured to it when the carrier is shifted to bring the cutter-shaft at right angles to the line of travel of the work. When the carrier is adjusted to this position, the coupling I' is detached from the shaft S and coupled to the shaft s³, 120 as indicated in dotted lines in Fig. 2. The cutter can then be used to cut a spline or keyway in the shaft which has been previously threaded, or a cut may be made in a plain shaft, if desired. The machine can be 125 used not only as a screw-cutting machine, but also to a certain extent as a keyway and spline cutter.

In order to hold the rod or bar to its work while the cutter is cutting the thread, we 130 mount a guide E on the slideway B, Figs. 1, 3, and 6, and this guide can be adjusted longitudinally on the slideway by means of a set-screw e, Fig. 1, so as to move it to either

side of the cutter *s*. The slide is usually in the position shown in the figures of the drawings when an ordinary thread is to be cut; but when it is desired to cut to a shoulder or head then the guide is moved to the opposite side of the cutter, so that the cut portion of the rod will rest in the guide. The guide has two transverse slides *E'*, controlled by an adjusting-screw *e'*, having a right and left hand thread, so that when the screw is turned the slides will be moved toward or from each other. Carried by the slides *E'* are jaws *e''*, held in place by bolts *e'''*. These jaws in the present instance are V-shaped, so as to properly grasp a cylindrical rod or tube.

The operation of the machine is as follows: If the parts are in the position shown in Fig. 1, the rod or tube to be cut is secured in the chuck-spindle *J* and in position under the cutter *s*, which has been set to the desired angle and clamped. Motion is then imparted to the carriage *D* through the screw-shaft and the driving-gear from the driving-shaft *H*, and as the lead-screw is turned the carriage will be moved forward at a certain speed, according to the arrangement of the gearing at the end of the machine, and the clutch-spindle and the rod will be turned according to the arrangement of the gears on the carriage, and as the work is fed to the cutter the cutter is rotated by the driving mechanism *III*², and the thread is cut on the rod. If the rod has a shoulder or head and it is desired to cut up to the head, then when the cutter reaches a point near the head the guide *E* is shifted to the opposite side of the cutter, so that the cutter can cut the thread up to the shoulder. If it is desired to cut two or more threads on a rod, so as to make it a double or triple threaded screw, then the cutter-carrier is so set as to make the pitch of the thread steep, and the gearing is changed so that the speed of the carriage will be increased, and when one thread is cut the sleeve *L* is turned, as remarked above, so as to turn the rod independently of the screw, so that the cutter will be in position between the grooves previously cut, and when the parts are locked the cutter will cut a second thread between the grooves of the preceding thread.

It will thus be seen that a machine built in accordance with our invention is simple in construction, can be used to cut a single thread on a rod or tube, or can be used to cut two or more threads, if desired, and the machine can be used to cut a keyway or spline in a shaft or in a screw-rod, if desired.

We claim as our invention—

60 1. The combination in a screw-cutting machine, of a bed, a slideway thereon, a carriage mounted on said slideway, a chuck-spindle on the carriage to which the work is secured, a longitudinally-arranged lead-screw on the bed, a clutch on the carriage engaging said lead-screw, a sleeve on the screw and carried

by the carriage, said sleeve having a key entering a spline in the lead-screw and geared to the chuck-spindle, and a cutter mounted to cut a thread on the rod as it is fed forward 70 by the lead-screw, substantially as described.

2. The combination in a screw-cutting machine, of a bed, a longitudinal keyway thereon, a longitudinal lead-screw parallel thereto, gearing for driving said lead-screw, a carriage 75 and a chuck-spindle both driven by said lead-screw, a carrier pivoted to the bed, a cutter-shaft mounted on the carrier, a cutter mounted on said shaft in the pivotal line of the carrier, a stud upon which the carrier is mounted, 80 and means for driving the cutter-shaft, substantially as described.

3. The combination of a bed, a carrier pivoted to one end of the bed, a cutter-shaft having its bearings in said carrier, a cutter thereon, a hollow driving-shaft at the opposite end of the bed, a splined driving-rod mounted in the hollow shaft and keyed thereto, a universal coupling connecting the said driving-rod to the cutter-shaft, a carriage, a lead-screw, 85 gearing by which the lead-screw is driven from the driving-shaft, and gearing by which the chuck-spindle on the carriage is driven from the lead-screw, substantially as described. 95

4. The combination in a screw-cutting machine of means for feeding a rod, a pivoted carrier, a cutter-shaft mounted in bearings in said carrier, a cutter on said shaft, means connected to the shaft for driving said cutter, said carrier being capable of adjustment on its pivot so that the cutter-shaft will be at right angles to the line of the work, and auxiliary mechanism for coupling said cutter-shaft to the driving mechanism when said shaft is in its adjusted position, substantially as described. 100

5. The combination of a bed, a pivoted carrier mounted on one end of the bed, a head, means for vertically adjusting said head, a 110 cutter-shaft on said head, a cutter, driving mechanism at the opposite end of the machine, the driving mechanism consisting of three rods coupled together by universal joints, one of said rods being connected to 115 the cutter-shaft, and means for feeding the work to the cutter, substantially as described.

6. The combination of a bed, a frame at one end of the bed, a driving-shaft mounted in said frame, a carrier pivoted to the opposite 120 end of said bed, a cutter-shaft mounted on the carrier, a cutter thereon, a longitudinal guideway, a longitudinal lead-screw, said screw being mounted in a bearing on one end of the machine and in the frame at the opposite end of the machine, a train of change-gears by which the lead-screw is driven from the driving-shaft, a carriage on the guideway, a chuck on the carriage engaging the lead-screw and by which the carriage is moved 125 toward or from the work, a hollow spindle on the carriage to which the work is clutched, 130

and change-gearing by which a rotary motion is imparted to the spindle from the lead-screw, substantially as described.

7. The combination in a screw-cutting machine, of a bed, a longitudinal lead-screw, means for turning said lead-screw, a carriage operated by the lead-screw, a chuck on the carriage to hold the work, a stud projecting from the under side of the bed, a carrier pivoted to said stud, means for clamping the carrier thereto, a head, and a cutter carried

by said head, said cutter being mounted in line with the pivot of the carrier, substantially as described.

In testimony whereof we have signed our names to this specification in the presence of two subscribing witnesses.
